UNITED STATES PATENT OFFICE

ANDREW WILLIAM MURPHY, OF NORWICH, NEW YORK

APPARATUS FOR SAVING RADIATOR ALCOHOL

Application filed May 18, 1931. Serial No. 538,364.

This invention relates to an apparatus for reclaiming the vapors of anti-freezing mixtures such as alcohol and water or their equivalent commonly used in the cooling systems of internal combustion engines and other heat-developing elements.

In cooling systems of this character the mixture is usually circulated through a jacket surrounding the heat generating element and thence through a cooling unit commonly known as a radiator having an overflow for excess liquid and vapor to prevent injury to the cooling system through excess expansion of the liquid under heat.

It is well-known that alcohol and similar anti-freezing agents commonly mixed with water in the cooling systems rapidly evaporate from the water through the overflow outlet, particularly under the increasing temperatures of the engine when in action, thus necessitating more or less frequent replenishing of the system with alcohol in order to maintain a safe anti-freezing mixture.

Aside from the monetary loss sustained by the escape of this alcoholic vapor to the atmosphere there is also always present the danger of lowering the alcoholic content in the mixture to such a degree as to permit freezing of the residue under varying degrees of freezing temperature.

The main object, therefore, of the present invention is to restore the alcoholic vapor to the cooling system immediately upon its liberation or escape through the overflow and thereby to render the use of this freezing mixture more economical and dependable under freezing temperatures.

Another object is to permit the mixture to be drawn off from the circulating chamber and placed in hermetically sealed receptacles for reuse at any time desired whether during the same or the succeeding season.

Other objects and uses relating to the detail construction of the apparatus will be brought out in the following description.

In the drawing:—

Figure 1 is an internal combustion engine and radiator forming a part of the

cooling system and my improved apparatus used in connection therewith.

Figure 2 is an enlarged sectional view, partly broken away, of the essential parts of the vapor-reclaiming apparatus as connected to and between the overflow of the radiator and return flow conduit of the mixture circulating system.

In order that the invention may be clearly understood I have shown portions of an internal combustion engine —A— having the usual jacket for receiving a liquid-cooling agent or mixture such as water and alcohol in proper proportions to form an anti-freezing mixture under varying freezing temperatures, said jacket being connected by up flow and return conduits —a— and —b— to a radiator —B— of any well known construction.

Any suitable means may be provided for circulating the cooling agent from the jacket to the radiator and return, but as illustrated the return conduit —b— is connected to an engine-driven pump —c— which not only draws the cooled mixture from the bottom of the radiator through the conduit —b— but also forces the cooling agent through the jacket and materially aids in the up flow of the heated mixture through the pipe —a— to the radiator to obtain a more rapid circulation of the cooling mixture through the jacket.

The radiator —B— is provided with the usual relatively small overflow pipe —d— leading downwardly from the top of the radiator near the inlet thereof to the atmosphere to permit the overflow of excess liquid and vapor, and thereby to serve as a relief vent for said radiator to prevent injury thereto by excess internal pressure of the heated fluid or vapor.

The device forming the subject matter of the present application preferably comprises a casting 1 having a cooling chamber 2 connected at one end by a pipe or conduit 3 to the overflow conduit —d—, the other end of the chamber 2 being connected by a pipe or conduit 4 to the return conduit —b— of the mixture-circulating system.

The conduit —d— includes therein a valve 100

case 5 containing a two-way valve 6 which, when adjusted to one position, as shown in Figure 2, cuts off the direct passage of the overflow through the conduit *d* to the atmosphere and directs the overflow through the conduit 3 and into the chamber 2 from which it is free to pass through the conduit 4 and into the return pipe *b* of the cooling system. It will be noted that the pipe *d* below the valve case 5 and the pipe 3 form two branches of the main overflow pipe and that the cooling chamber 2 and pipe 4 form continuations of the branch pipe 3 for connection with the return flow conduit *b*.

The valve is preferably adjusted to this position when an anti-freezing agent such as alcohol is used in the cooling mixture for preventing the escape of the mixture or its vapor through the overflow to the atmosphere and causing said mixture to be restored to the circulating system through the chamber 2 and conduit 4.

On the other hand, when no anti-freezing agent is required in the cooling system, the valve 6 may be adjusted to cut off communication between the overflow *d* and conduit 3 and to allow the direct passage of vapor and excess liquid from the top of the radiator through the overflow and to the atmosphere in the usual manner.

The delivery conduit 4 is shown as connected directly to the return flow conduit *b* of the cooling system but obviously may be connected to any other part of said system capable of returning the vapor of the anti-freezing agent to said system immediately following its escape into the overflow *d* of the radiator.

The conduit 4 is provided with a check valve 7 arranged to prevent the backflow of the cooling mixture from the conduit *b* into the chamber 2 while permitting free flow of the vapor or condensation through said conduit to the pipe *b*.

In fact, the suction produced in the conduit *b* by the pump *c* has a similar but less suction for the pipe 4 to assist in drawing the collected vapor from the chamber 2 into the cooling system.

The chamber 2 is provided with an air vent 8 controlled by a valve 9 which is yieldingly held in its closed position by a coil spring 10, but is adapted to be opened against the action of the spring in case the vacuous condition in the chamber 2 should become excessive as a result of the action of the pump *c*, thereby preventing excessive suction in the pipe 3 and overflow *d* of the radiator.

The chamber 2 is provided with a branch outlet 11 which is adapted to discharge to atmosphere through a conduit 12 but is controlled by a valve 13 which is yieldingly

held in its closed position by a spring 14, Figure 2.

This valve 13 is adapted to be opened by excess liquid or vapor pressure within the chamber 2 due to overheating of the liquid or vapor in the radiator to which it is connected, under which conditions the vapor or liquid under excess pressure would escape to the atmosphere through the outlets 11 and 12. As previously explained, the cooling chamber 2 and pipe 4 form continuations of the branch pipe 3 of the main overflow pipe *d* and as such, this branch is provided with pressure relief passages 11 and 12 and controlling valve therefor and is also provided with the vacuum relief passage 8 and controlling valve 9.

Operation

When the water jacket of the engine and radiator are filled more or less with a cooling mixture containing an anti-freezing ingredient such as alcohol or equivalent rapidly evaporating liquid, communication of the overflow conduit *b* with the atmosphere will be cut off by proper adjustment of the valve 6 so that when the engine is running and developing heat, thereby heating the cooling liquid, the latter will be caused to circulate from the water jacket of the engine to the radiator and return from the radiator to the jacket through the pipes *a* and *b*, thereby establishing what may be termed a closed circulating system.

As the anti-freezing mixture evaporates or overflows into the pipe *d*, it will be conducted through the pipe 3 into the chamber 2 and thence through the pipe 4 into the suction side *b* of the pump *c*, thereby effecting a continuous return and reuse of the evaporated mixture without appreciable loss of the alcohol content.

Whenever desired, as for example when freezing weather ceases, the entire cooling mixture may be withdrawn from the circulating system and preserved in hermetically sealed receptacles for future use.

The circulating system may then be refilled with water or similar comparatively inexpensive liquid for engine-cooling purposes, at which time the valve 6 in the overflow pipe *d* will be adjusted to close communication with the chamber 2 and open communication with the atmosphere.

In case the degree of vacuum within the chamber 2 should be excessive it will immediately cause the valve 9 to open to admit atmospheric air and thereby to break the excessive vacuum. On the other hand, if the pressure from the radiator in the overflow pipe should be excessive the valve 13 would be opened against the action of its spring 14 to allow the excess pressure to vent itself to the atmosphere through the pipe 12.

The device shown, particularly in Figure 2, may be made and sold at a comparatively low cost and easily and quickly installed upon the engine or its supporting frame 5 without material alterations of any of the usual parts other than the mere connections of the pipes 3 and 4 to the overflow pipe —*d*— and suction side —*b*— of the circulating system, but it is evident that the structural 10 details and manner of connecting the device to the circulating system may be varied without departing from the spirit of the invention.

What I claim is:—

15 1. The combination with the cooling system of an internal combustion engine including the usual water jacket and radiator and the upflow and return pipes connecting the jacket and radiator, of an overflow pipe 20 leading from the interior of the upper portion of the radiator and provided with two branches, one of said branches being open to the atmosphere, the other branch being connected to one of the first named pipes, 25 and means for diverting the overflow to either of said branches and for cutting off the passage of the overflow to the other branch.

2. A cooling system for internal combustion engines as in claim 1 in which one of the branch overflow pipes is provided with a pressure-relief passage opening to the atmosphere, and a self-closing valve controlling said passage and adapted to be opened 35 by excess pressure in said branch pipe.

3. A cooling system for internal combustion engines as in claim 1 in which one of the branch overflow pipes is provided with a vacuum relief passage opening to the atmosphere, and a self-closing valve controlling said passage and adapted to be opened 40 by excess vacuum in said branch pipe.

In witness whereof I have hereunto set my hand this 8th day of May, 1931.
